UNITED STATES PATENT OFFICE.

WALTER T. JANNEY, OF PHILADELPHIA, PENNSYLVANIA.

CENTRIFUGAL CASTING MACHINE.

Application filed September 13, 1922. Serial No. 587,993.

To all whom it may concern:

Be it known that I, WALTER T. JANNEY, a citizen of the United States, residing at Philadelphia, in the county of Philadelphia and State of Pennsylvania, have invented certain new and useful Improvements in Centrifugal Casting Machines, of which the following is a specification.

My invention relates to centrifugal casting machines in which the revoluble mold is movable relatively to its support, and is yieldingly held in operative position thereon by compressed air. The device is related to the constructions set forth in my pending applications Nos. 573,019, 580,162.

My object is to employ compressed air for yieldingly holding the mold in its operative position, so as to adequately take care of the expansion and contraction which inevitably take place in a mold of this character when in use.

Another object is to provide means for the employment of the air which presses the mold for also cooling the mold during the casting operation.

Other objects will appear in the subjoined description.

An important feature of the invention consists of a revoluble basket having a lid rigidly held thereon against outward movement; and a mold carried inside the basket; and means including compressed air for yieldingly holding the mold in engagement with the lid.

The invention consists in certain novel features of construction and arrangement of parts, as will be hereinafter described and claimed, reference being had to the accompanying drawings, in which:—

Fig. 1 is a sectional view of my device.

Fig. 2 is a side elevation of the plunger.

Fig. 3 is an end elevation of Fig. 2, looking toward the right.

Fig. 4 is a front-end elevation of the device.

Fig. 5 is a plan view of the lid of the device.

Fig. 6 is a sectional view of Fig. 5.

Fig. 7 is an end view of the mold or die, the mold being shown in this view as formed in two sections spaced from each other for better illustration.

Fig. 8 is a side elevation of Fig. 7; and,

Fig. 9 is a broken sectional side elevation of one of the castings formed in the mold illustrated in Figs. 1, 7 and 8.

In my construction herein shown, instead of the lid being held on the mold, as is ordinarily the case, the mold is yieldingly held against the lid—is held in a casing which serves as a guide for its movements, so that when a horizontal mold is standing still, the mold will have no disposition to move out of engagement with the lid, but even if it did, the fact that the mold has guided movement relatively to the lid, would cause it to move back into proper engagement therewith whether pressed by compressed air, spring force, centrifugal force, or any other force whatsoever: so that the great advantage of having a stationary lid cooperating with a movable mold becomes very apparent.

Referring to the drawings, the numeral 1 indicates a housing having a large central opening 2 at its forward end, and at its inner end an integral sleeve into which is cast a long bearing 4, which supports a hollow shaft 5, having at its inner end inside the housing 1, a heavy flange 6, and beyond the sleeve 3 of the housing, a pulley 7 rigidly held thereon. A basket 8 is rigidly held on the flange 6 by stud bolts 9, and loosely fitting inside this basket is a mold cup 10 which serves as a container for the two halves of the split die or mold 11, it being understood, of course, that the die may be divided into more than two sections if desired.

A lid 12 holds the cup 10 and the die 11 in the basket 8. The lid is provided on its inner side with an annular inclined face 13, and the bottom of the cup 10 has a correspondingly inclined face 14. The two ends of the sectional mold or die are frustoconical in shape with their annular inclined faces 15 and 16 adapted to fit the annular inclined faces 13 and 14 of the cup 10 and the lid 12.

The length of the die relatively to the depth of the cup is always such that the cup and lid cannot quite touch each other.

When compressed air is admitted into the hollow shaft 5, the piston 21 presses the cup 10 outwardly, and with it the sectional die 11, which in turn presses the lid into engagement with the lugs 18 at the open end of the basket 8.

The lid 12 is provided with a central opening 12^a and annular slots 17 the exterior diameter of which is equal to the interior diameter of the casting 11^a to be formed.

- The basket is provided with four inwardly extending lugs 18 behind which the four outwardly projecting lugs 19 are received, as more clearly illustrated in Fig. 4.
- 5 The opening in the hollow shaft 5 is suitably enlarged at its inner end to receive the plunger 20 which has a piston 21 at its inner end and a smaller piston 22 at its outer end provided with longitudinal slots 23 (see
- 10 Figs. 2 and 3). The stem of the plunger 20 carries a compression spring 24 which is received around said stem between the small piston 22 and the thrust plate 23^a which is rigidly secured to the shaft 5 which has a
- 15 central opening 25 adapted to snugly receive said stem 20, by which arrangement the plunger has imparted to it by the spring a tendency to always move outwardly.
- 20 A stationary compressed air pipe 26 carried by a support 27 extends into the outer end of the hollow shaft 5, and is suitably packed at 28 to prevent the escape of air. This pipe 26 connects with a source of supply of compressed air, and is controlled by
- 25 a valve 29, having a turn plug 29^a.
- In order that a continuous current of air may pass around the mold cup 10 during the casting operation, to cool the same, I provide one or more small bores 30 in the piston 21. When the machine is stopped these bores also serve for the quick release of any compressed air that might otherwise be imprisoned in the hollow shaft 5, and thus permit the pressure to be quickly removed from
- 30 against the lid when the machine is stopped, so that the lid can be easily removed.
- 35 The easy and quick removal of the lid provided for in my device, permits the machine to be operated, time after time, in rapid succession.
- 40 The thickness of the wall of the casting is determined by the position of the curved slots 17, so that only a differently slotted lid is necessary to produce a casting with a
- 45 thicker or a thinner wall.
- Having described my invention, what I claim as new and desire to protect by Letters Patent is:—
1. In centrifugal casting machines, a revoluble basket open at its front end; a mold received into the basket; a lid held at the open end of the basket, the mold being movable relatively to the lid; a plunger for pressing the mold into engagement with the
- 50 lid; means for operating the plunger with compressed air, said parts having means for the escape of a portion of the compressed air into the revoluble basket to cool the mold.
- 55 2. In centrifugal casting machines, a revoluble basket; a mold held in the basket and movable relatively thereto, said basket having a chamber at the rear side thereof in communication with the bottom of the mold; a plunger mounted in said chamber to move toward and from the mold; a spring for normally pressing the plunger in a direction away from the mold; means for introducing compressed air into the chamber behind the plunger for overcoming the force of the spring and yieldingly pressing the plunger against the mold, the device being provided with means for relieving the air pressure in the chamber behind the plunger when the air supply is cut off, whereby to permit the opposing spring to promptly retract the plunger.
- 60 3. In centrifugal casting machines, a revoluble basket; a mold held in the basket and movable relatively thereto, said basket having a chamber at the rear side thereof in communication with the bottom of the mold; a plunger mounted in said chamber to move toward and from the mold; a spring for normally pressing the plunger in a direction away from the mold; means for introducing compressed air into the chamber behind the plunger for overcoming the force of the spring and yieldingly pressing the plunger against the mold, the device being provided with an opening between the interior of the basket and the portion of the plunger-chamber behind the plunger.
- 65 4. In centrifugal casting machines, a revoluble basket open at its front end; a mold received into the basket; a lid held at the open end of the basket, the mold being movable relatively to the lid, said basket having a hollow shaft at its rear side rotating therewith and provided with a chamber in communication with the interior of the basket; a plunger mounted in said chamber to move toward and from the mold; a stationary pipe adapted to be connected at its outer end with a source of supply of compressed air, and entered at its inner end into said hollow shaft to introduce compressed air to the plunger; and a packing box at the outer end of the revolving shaft surrounding the inner end of said stationary pipe to form an air-tight connection between the two, said plunger having an opening therethrough for the escape of a portion of the compressed air into the revoluble basket to cool the mold.
- 70 105 110 115
- In testimony whereof I affix my signature.

WALTER T. JANNEY.
